UNITED STATES PATENT OFFICE.

JOHN F. O'CONNOR, OF CHICAGO, ILLINOIS, ASSIGNOR TO WILLIAM H. MINER, OF CHAZY, NEW YORK.

FRICTION SHOCK-ABSORBING MECHANISM.

Application filed October 4, 1920. Serial No. 414,663.

To all whom it may concern:

Be it known that I, JOHN F. O'CONNOR, a citizen of United States, residing at Chicago, in the county of Cook and State of Illinois, have invented a certain new and useful Improvement in Friction Shock-Absorbing Mechanisms, of which the following is a full, clear, concise, and exact description, reference being had to the accompanying drawings, forming a part of this specification.

This invention relates to improvements in friction shock-absorbing mechanisms.

One object of the invention is to provide a friction shock absorbing mechanism adapted more particularly for railway draft riggings and specifically for locomotive tenders, the mechanism having unusually high capacity.

More specifically, the object of the invention is to provide a friction shock absorbing mechanism having a large number of separate sets of friction surfaces combined with a large number of springs, the arrangement being such that wear on the friction parts may be automatically compensated for.

In the drawing forming a part of this specification, Figure 1 is a horizontal longitudinal sectional view of a portion of a railway draft rigging showing my improvements in connection therewith. Figure 2 is a vertical longitudinal sectional view corresponding substantially to the line 2—2 of Figure 1. Figures 3 and 4 are vertical transverse sectional views corresponding to the lines 3—3 and 4—4 respectively in Figure 1. And Figure 5 is a detailed perspective of a block employed with my improvements.

In said drawings, 10—10 denote channel center or draft sills of a railway car to the inner faces of which are secured front stop lugs 11 and rear stop lugs 12. The rear portion of the draw bar is indicated at 13, the same being operatively associated with the shock absorbing mechanism proper by a hooded elongated cast yoke 14 and coupler key 15. The yoke and associated movable parts are supported by detachable saddle plates 16—16.

The improved shock absorbing mechanism as shown, comprises broadly, a heavy shell casting A; a pair of combined friction shoes

and spring followers B—B; a plurality of transversely arranged coil springs C—C; a front main follower D; a pair of longitudinally arranged preliminary coil springs E—E; and a pair of followers G—G.

The casting A, in over-all width, corresponds approximately to the space between the draft sills, said casting being of generally rectangular outline and with a rear integral wall 17 adapted to co-operate with the stop lugs 12. On the interior, the shell casting A is provided on each side of the longitudinal center line thereof with sets of friction surfaces 18—18 on one side and 118—118 on the other side. All of the friction surfaces 18 of the one set extend in the same general direction, that is, the same are inclined inwardly and rearwardly toward the center of the shell. The friction surfaces 118 of the other set are correspondingly all inclined in the same direction, that is, rearwardly and inwardly of the shell. The interior of the casting A is also formed with a plurality of transversely extending shoulders 19—19 at the outer ends of each of the friction surfaces 18 and 118.

The combined spring followers and friction shoes B are of like construction and each is in the nature of an elongated element of U cross-section as indicated most clearly in Figure 4, that is, the top and bottom arms of the U indicated at 20 and 21 extend horizontally and are connected by a vertical web 22. On the outer side, each member B is formed with a series of inclined friction surfaces 24—24 corresponding in slope to and co-operable with the respective shell friction surfaces 18 and 118. The members B are also provided with transversely extending shoulders 25 normally disposed adjacent to but slightly spaced from the transversely extending shoulders 19 of the shell. In normal position of the members B, they are separated as clearly shown in Figure 1 but the same are adapted to come together upon full compression of the mechanism.

The springs C are shown as five in number and preferably one for each set of opposed friction surfaces 18 and 118. As clearly indicated in Figure 1, the springs C are confined within the members B and are not only compressible laterally but will

move longitudinally in unison with the members B. At the outer ends of the members B, detachable blocks F are employed, one for each member B. Each block F has 5 a concave inner face 26 conforming to the outermost springs C so as to properly guide and center the latter. The blocks F are furthermore formed with squared lugs 27 and 28 engaging in correspondingly shaped 10 slots in the members B to hold the blocks in proper relation therewith.

The front main follower D is formed with an inwardly extended rectangular casing 29 adapted to telescope within the open or mouth end of the friction shell casting A. As will be seen from an inspection of Figures 1 and 2, the follower D is provided with shoulders 30 surrounding the casing 29 which shoulders will engage with the 15 outer end 31 of the friction shell to limit relative movement between the follower D and shell casting A. The two preliminary springs E are disposed within the casing 29, said springs being centered on bosses 32 formed on the follower D and other bosses 33 formed on the outer side of the two followers G. Connecting bolts 34-34 are employed between the outer follower D and the other two followers G. The latter are slipped within the shell between the outer ends of the members B and the outermost set of transversely extending shell shoulders 19, as clearly shown in Figure 1. Only a comparatively small space is left 20 between the inner edge of the casing 29 and the followers G for the preliminary spring action.

The operation is as follows, assuming a pulling or draft movement of the draw bar. 40 As the draw bar moves outwardly under draft, the friction shell casting A will be pulled in the same direction in unison therewith. The front follower D will of course remain stationary in its engagement with the front stop lugs 11. During the first portion of the outward movement of the shell casting A, no frictional action will occur but on the contrary merely a spring action in the springs E until the followers 45 G engage the inner edge of the casing 29. Thereafter the followers G will be held stationary and the members B prevented from longitudinal movement outwardly with the friction shell A. As the friction 50 shell A continues its outward movement, it is evident that the inclined friction surfaces 18 and 118 thereof will force or squeeze the elements B inwardly toward each other, thus generating a great amount 55 of friction between all of the sets of co-operating inclined friction surfaces, the frictional resistance being augmented by the spring resistance. The outward movement 60 of the friction shell A may continue until 65 it engages with the shoulders 30 of the front

follower D. In buffing, as will be understood by those skilled in the art, the friction shell remains stationary and the follower D and members B are moved relatively rearwardly to the friction shell A 70 with an action similar to that before described.

In assembling the mechanism, the elements B are first inserted within the casting A after which the springs are inserted between the members B, it being understood that the blocks F are not in place when this is done. After the springs are in place, the blocks F are inserted and then the followers G are forced home between the 75 ends of the members B and the outermost set of shoulders 19. The parts are so constructed, that during the last operation mentioned, the elements B will be forced rearwardly a slight amount so as to leave 80 spaces between the shoulders 25 and 19. The reason for leaving the spaces indicated is to permit the elements B to laterally adjust themselves to compensate for wear on the various friction surfaces. The follower 85 D and springs E are applied last, as will be understood.

I have herein shown and described what I now consider the preferred manner of carrying out the invention, but the same is 90 merely illustrative and I contemplate all changes and modifications that come within the scope of the claims appended hereto.

I claim:

1. In a friction shock absorbing mechanism, the combination with a longitudinally movable friction shell having a pair of opposed sets of interior friction surfaces, each set including a plurality of friction surfaces all inclined in the same direction relatively to the centre line of the shell, said shell being provided also with a plurality of interior transversely extending shoulders adjacent said friction surfaces of the shell; of a pair of friction shoes within the shell, each shoe having a plurality of outer friction surfaces co-operable with those of one set of the shell, each shoe having also a plurality of transversely extending shoulders normally disposed opposite the corresponding shoulders of the shell; spring means interposed between said shoes adapted to yieldingly resist relative movement therebetween; an auxiliary spring resistance; a spring follower interposed between said auxiliary spring resistance and the ends of said shoes; and a front follower co-acting with said auxiliary spring resistance, said front follower having means thereon adapted to engage the spring follower to limit the compression of the auxiliary spring resistance and transmit the pressure directly to said spring follower.

2. In a friction shock absorbing mechanism, the combination with a longitudinally movable friction shell having a pair of op-

posed sets of interior friction surfaces; of a pair of friction shoes within the shell, each shoe having a plurality of outer friction surfaces cooperable with those of one set of the shell; a plurality of transversely arranged coil springs interposed between said shoes; and a removable block detachably mounted on the outer end of each shoe, said block

having its interior conformed to center the adjacent transversely extending coil spring. ¹⁰

In witness that I claim the foregoing I have hereunto subscribed my name this 15th day of Sept., 1920.

JOHN F. O'CONNOR.
